(57) **CLAIM**

The ornamental design for a display screen or portion thereof with graphical user interface, as shown and described.

DESCRIPTION

The FIGURE is a front view of a display screen or portion thereof with graphical user interface showing our new design. The dash-dot broken lines in the drawings illustrate the bounds of a display screen or a portion thereof, whereas the even broken lines illustrate portions of the graphical user interface. Neither broken line showings form part of the claimed design.
